EDUCATIONAL TOOL TOY

Mark Carpenter, McKenzie, Ala.

Application March 20, 1958, Serial No. 50,109

Term of patent 7 years

(Cl. D34—15)

Fig. 1 is a perspective view of an educational tool toy, showing my new design;

Fig. 2 is a top plan view;

Fig. 3 is a bottom plan view; and

Fig. 4 is a view in side elevation.

What I claim is:

The ornamental design for an educational tool toy, as shown.
